CLAIM

We claim the ornamental design for an upper heating and weighing pan, as shown and described.

DESCRIPTION

FIG. 1 is a front perspective view of FIG. 3;
FIG. 2 is a top perspective view from a different angle of FIG. 3;

FIG. 3 is a front vertical view of an upper heating and weighing pan;

FIG. 4 is a top plan view of FIG. 3;

FIG. 5 is a left side view of FIG. 3;

FIG. 6 is a right side view of FIG. 3;

FIG. 7 is a rear view of FIG. 3; and,

FIG. 8 is a bottom view of FIG. 3.

The broken lines illustrate portions of the upper heating and weighing pan that form no part of the claimed design.
